UNITED STATES PATENT OFFICE.

EMANUEL K. LECRONE, OF YORK, PENNSYLVANIA, ASSIGNOR OF ONE-HALF
TO ANDREW C. FULTON, OF SAME PLACE.

WASHING-MACHINE.

SPECIFICATION forming part of Letters Patent No. 362,019, dated April 26, 1887.

Application filed November 29, 1886. Serial No. 220,145. (No model.)

To all whom it may concern:

Be it known that I, EMANUEL K. LECRONE, a citizen of the United States, and a resident of York, in the county of York and State of Pennsylvania, have invented certain new and useful Improvements in Washing-Machines; and I do hereby declare that the following is a full, clear, and exact description of the invention, which will enable others skilled in the art to which it appertains to make and use the same, reference being had to the accompanying drawings, which form a part of this specification, and in which--

Figure 1 is a longitudinal vertical sectional view of my improved washing-machine. Fig. 2 is a side view of the machine with one side piece removed; and Fig. 3 is a top view.

Similar numerals of reference indicate corresponding parts in all the figures.

My invention has relation to that class of washing-machines in which the two rubbing elements are reciprocated toward each other; and it consists in the improved construction and combination of parts of such a machine, as hereinafter more fully described and claimed.

In the accompanying drawings, the numeral 1 indicates the rectangular suds-box, which is mounted upon legs 2, and formed with two vertical slots, 3, in one end piece, the slots extending from the upper edge.

Two blocks, 4, having concave inner edges, 5, slide with their upper and lower edges between the bottom of the suds-box and two cleats, 6, secured to the inner sides of the side pieces of the suds-box at their upper edges, and a block, 7, having a concave inner face, 8, formed with corrugations or transverse ribs 9, is secured to the blocks with its ends and has its lower edge extending nearly to the bottom of the suds-box. A coiled spring, 10, or similar elastic spring, is secured to the outer face of this concave block, and is secured to the end piece of the suds-box, serving to draw the block back when it has been drawn toward the middle of the suds-box.

A rubber or block, 11, is pivoted with trunnions 12 in its ends between the side pieces of the suds-box, and the lower portion of this block or rubber is formed with a convex ribbed or corrugated face, 13, eccentric to the trunnions and corresponding in curve to the con-

cave face of the other sliding block. Curved arms 14 are secured to the outer side of the convex rubber at the upper edge of the same, and the outer ends of these arms are connected by means of a handle, 15, the arms projecting through and rocking in the slots in the end piece of the suds-box. The ends of the convex rubber are formed with recesses 16, near the upper edge, and bolts or trunnions 17 project in these recesses, and have arms 18, pivoted to the other ends of these arms, rocking in triangular recesses 19 in the sliding blocks of the concave rubber, and having springs 20 at their ends, which springs are secured to the said blocks at the pointed ends of the recesses.

It will now be seen that when the convex rubber is reciprocated or rocked by means of its handle the arms pivoted to its ends near the upper edge will reciprocate the concave rubber or block, which will slide forward and back in the end of the suds-box, with its end blocks sliding between the bottom and the cleats, and the clothes which are placed in the suds-box between the two rubbers will be compressed and pounded between the two rubbers and at the same time be rolled as the convex face of the rocking rubber will be drawn upward and down over the concave face of the reciprocating rubber, so that the clothes will be subjected to a pounding as well as a rubbing. The springs at the ends of the arms connecting the rocking rubber with the reciprocating rubber will allow one end of the reciprocating rubber to yield more than the other end, in case that the clothes should fill up more space at one end of the rubber than at the other, and both springs together will prevent any undue pressure upon the clothes by the two rubbers. The suds will be considerably agitated in the suds-box and may pass over the reciprocating rubber and under the lower edge of the same, there being a small space between the said lower edge and the bottom, and the suds may pass freely under the rocking rubber, so that the circulation or splashing forward and back of the suds will assist in washing the clothes, together with the action of the rubbers.

Having thus described my invention, I claim and desire to secure by Letters Patent of the United States--

1. In a washing-machine, the combination of

a rocking rubber having a convex face at its lower portion, a reciprocating rubber having a concave face registering with the convex face of the other rubber, arms pivoted to the ends 5 of the rocking rubber eccentric to the trunnions of the same and to the ends of the reciprocating rubber, and an elastic spring secured to the back of the reciprocating rubber and to the end piece of the suds-box, as and for the 10 purpose shown and set forth.

2. In a washing-machine, the combination of a rocking rubber having its trunnions at the middles of the ends, and having a convex face at its lower portion eccentric to the trunnions, 15 a reciprocating rubber having a concave face and having end pieces sliding in the sides of the suds-box, an elastic spring secured to the back of the concave rubber and to the end piece of the suds-box, and arms pivoted to the 20 ends of the rocking rubber eccentric to the trunnions, and having yielding and movable connections at their other ends to the end pieces of the reciprocating rubber, as and for the purpose shown and set forth.

25 3. In a washing-machine, the combination of a suds-box having vertical slots in the edge of one end piece, and having horizontal cleats secured to the inner sides of the side pieces at the upper edges and near one end of the same,

blocks with their lower edges sliding upon the 30 bottom of the suds-box and their upper edges sliding under the cleats, said blocks being formed with triangular recesses in their outer sides near the upper edges, a concave ribbed rubber secured with its ends in the blocks, an 35 elastic spring secured to the back of this rubber and to the end piece of the suds-box, a rubber having trunnions at the middles of its ends pivoted between the side pieces of the suds-box and formed with a convex ribbed face at 40 its lower portion eccentric to the trunnions, and with recesses in the upper portions of the ends located in said recesses, bolts, arms projecting from the upper portion of the back of the rocking rubber and having a handle connecting them, and arms pivoted to the bolts in the recesses in the ends of the rocking rubber, and having yielding springs connecting their other ends to the recessed end pieces of the reciprocating rubber, as and for the purpose 45 50 shown and set forth.

In testimony that I claim the foregoing as my own I have hereunto affixed my signature in presence of two witnesses.

EMANUEL K. LECRONE.
